UNITED STATES PATENT OFFICE.

JONATHAN H. VAIL, OF NORRISTOWN, PENNSYLVANIA, ASSIGNOR TO PENNSYLVANIA IRON WORKS COMPANY, OF PHILADELPHIA, PENNSYLVANIA, A CORPORATION OF PENNSYLVANIA.

VAPORIZER FOR INTERNAL-COMBUSTION ENGINES.

No. 837,984.

Specification of Letters Patent.

Patented Dec. 11, 1906.

Application filed March 23, 1904. Serial No. 199,607.

To all whom it may concern:

Be it known that I, JONATHAN H. VAIL, of Norristown, in the State of Pennsylvania, have invented certain new and useful Improvements in Vaporizers for Internal-Combustion Engines, whereof the following is a specification, reference being had to the accompanying drawings.

My improvements relate to the arrangement of the inlet-chamber for the vaporizer; to the collocation, adjustment, and control of the air and fuel inlet valves; to the screen interposed between said two inlet-valves; to air-deflectors on the air-inlet valve, and the jacketing system for the vaporizer.

In the drawings, Figure I is a central vertical section of a vaporizer embodying my invention. Fig. II is a plan view of the screen. Fig. III is a plan view of the air-inlet valve, showing the deflectors.

In the drawings, 1 is the inlet-chamber casing, having the air-inlet on its under side comprising the conical seat for the valve 2. Said valve 2 is provided with the spindle 3, which is screw-threaded in said valve and adjustable from the exterior of said casing 1 to determine the extent of projection of its end 4 above said valve. Said valve 2 is provided at its top with deflecting-plates 5, which are preferably curved, as shown in plan in Fig. III, so that the air entering obliquely between the opposing surfaces of said valve 2 and its seat is distributed in the casing 1. The spider-frame 6, above said valve-casing 1, comprises the central tubular valve-casing provided with the conical seat 7. Said seat 7 communicates with the passage-way 8 in one of the arms of said frame 6, through which the liquid fuel is admitted from the pipe 10 under control of the valve 9. The needle-valve 11 is fitted to said seat 7 and provided with the coiled spring 12, which abuts upon its shoulder within the adjustable cap 13, which latter is screwed into said casing above said seat, so that said valve 11 is normally maintained in the closed position shown. Said valve 11 depends above the end 4 of the valve-stem 3 and in alignment therewith, so that when the valve 2 is opened the valve 11 is also opened to an extent determined by the adjustment of said stem 3, and both air and liquid fuel are contemporaneously admitted to the inlet-chamber 1.

The vaporizing-chamber above the spider-frame 6 is surrounded by the inner shell 14 and the outer casing 15, between which is a space or jacket for a heated medium, such as the products of combustion from the engine, supplied and withdrawn through the pipes 22 and 23, respectively. The upper end of the vaporizer-easing is provided with the annular head 17, through which the mixture of fuel and air passes to the auxiliary chamber 18, which has the outlet 19, leading to the engine.

The fuel admitted when the needle-valve 11 is uplifted falls upon the screen, which consists of two upwardly-convexed foraminous disks 24 of different curvature, which are separated at their central portions and united at their edges to the annular trough-shaped rim 25, which is supported by the annular flange 26, attached to the casing 1. Said screen-disks are preferably provided with openings through which the valve 11 may freely reciprocate. It is to be understood that the upwardly-convexed form of said screen facilitates the radial distribution of the fuel which is received at its central portion, and such portion of the fuel as is not atomized and carried up from the upper disk gravitates upon the lower disk or into the trough 25 and is absorbed therefrom by the air admitted around the valve 2. Although I prefer to form said screen of two foraminous disks separate from the valve 11, it may consist of a single foraminous disk attached to said valve, in which case the flange 26 may be omitted.

The operation of my device is as follows: The unseating of the air-inlet valve 2 admits a strong inrush of air through the inlet-chamber and at the same time lifts the valve 11, permitting liquid fuel to drip down and distribute itself upon the screen. The inrushing air passing through this screen partially atomizes and partially vaporizes this liquid fuel, carrying it up with it into the vaporizing-chamber, where the heat which results from its surrounding jacket completes the vaporization of that portion of the fuel which has previously been only atomized, thus bringing about a very effectual and complete vaporization of the charge for the engine.

I do not desire to limit myself to the precise details of construction and arrangement

herein set forth, as it is obvious that various modifications may be made therein without departing from the essential features of my invention.

5. I claim—

1. A vaporizer for an internal-combustion engine comprising an inlet-chamber fitted with an air-inlet valve upon its lower side, a liquid-fuel inlet-valve above it, and a screen 10 mounted within the inlet-chamber between said two valves, whereby the fuel is atomized and partially vaporized; and a jacketed vaporizing-chamber immediately above the inlet-chamber whereby the vaporization of the fuel is completed, substantially as set forth.

2. A vaporizer for an internal-combustion engine comprising an inlet-chamber having air and fuel inlet valves with a screen interposed between them; and a vaporizing-chamber 20 in juxtaposition and free communication with said inlet-chamber, with a jacket surrounding said vaporizing-chamber, in combination with means for leading the exhaust of the engine through the jacket whereby fuel atomized in the inlet-chamber may be 25 completely vaporized, substantially as set forth.

3. A vaporizer for an internal-combustion engine comprising air and liquid fuel inlet 30 valves in vertical alinement with each other, the latter being uppermost, and arranged to discharge in the direction of the air-inlet valve; and a screen convexed toward the direction in which the fuel-valve discharges, 35 interposed axially between said valves, whereby the fuel which is discharged upon it is distributed as the air is drawn through the screen, substantially as set forth.

4. A vaporizer for an internal-combustion 40 engine, comprising air and liquid fuel inlet valves in vertical alinement with each other, the latter being uppermost and discharging downwardly toward the former; and a plurality of upwardly-convexed screens interposed between said two valves, substantially 45 as set forth.

5. A vaporizer for an internal-combustion engine comprising air and liquid fuel inlet valves in alinement with each other, the latter being uppermost; and, an upwardly-convexed screen interposed between said valves, and having an imperforate trough-shaped rim, substantially as set forth. 50

6. A vaporizer for an internal-combustion engine, comprising air and liquid fuel inlet 55 valves in alinement with each other, the latter being uppermost; and, two upwardly-convexed disk-shaped screens united at their edges to an imperforate trough-shaped rim, interposed between said valves, substantially 60 as set forth.

7. A vaporizer for an internal-combustion engine comprising a needle-valve for the admission of fuel; a screen below the seat of the needle-valve, through which a projecting end 65 of the needle-valve extends; and, means for passing air upwardly through the screen, substantially as set forth.

8. In a vaporizer for an internal-combustion engine, an air-inlet valve having a conical seat; and, a series of curved vertical deflecting-plates mounted on the upper side of 70 said valve and projecting over its edge, substantially as set forth.

9. In a vaporizer for an internal-combustion engine, the combination of air and fuel inlet valves in alinement with each other; and a stem adjustably mounted within said air-inlet valve and projecting above the same to engage the lower end of the fuel-inlet valve, 75 whereby by the adjustment of said stem the extent of the engagement of the valves with each other may be regulated, substantially as set forth. 80

In testimony whereof I have hereunto 85 signed my name, at Philadelphia, Pennsylvania, this 9th day of March, 1904.

JONATHAN H. VAIL.
